US00D740036S

(12) United States Design Patent
Choi et al.

(10) Patent No.: US D740,036 S
(45) Date of Patent:  Oct. 6, 2015

(54) FABRIC

- (71) Applicant: SUNG JOO D&D, INC., Seoul (KR)
(72) Inventors: Eun-young Choi, Seoul (KR); Ji-won Park, Seoul (KR)
(73) Assignee: Sung Joo D&D, Inc., Seoul (KR)
() Term: 14 Years
(21) Appl. No.: 29/475,282
(22) Filed: Dec. 2, 2013

(30) Foreign Application Priority Data

- Nov. 22, 2012 (KR) 30-2013-0058922
(51) LOC (10) Cl. 05-05
(52) U.S. Cl. D5/61
USPC D5/61

(57) CLAIM

The ornamental design for a fabric, as shown and described.

DESCRIPTION

The sole FIGURE is a top plan view of a fabric, showing our new design. The fabric is planar.

1 Claim, 1 Drawing Sheet

U.S. Patent

Oct. 6, 2015

US D740,036 S

UNITED STATES PATENT AND TRADEMARK OFFICE
CERTIFICATE OF CORRECTION

PATENT NO. : D740,036 S
APPLICATION NO. : 29/475282
DATED : October 6, 2015
INVENTOR(S) : Eun-young Choi et al.

It is certified that error appears in the above-identified patent and that said Letters Patent is hereby corrected as shown below:

On the title page item [30], Column 1, Line 1, delete "Nov. 22, 2012" and insert -- Nov. 22, 2013 --, therefor.

Signed and Sealed this
Tenth Day of May, 2016

Michelle K. Lee
Director of the United States Patent and Trademark Office
